UNITED STATES PATENT OFFICE

JOHN J. SPARLOW, OF SWOYERSVILLE, PENNSYLVANIA

TOY

Application filed October 10, 1931. Serial No. 568,215.

This invention relates generally to toys and particularly to toys of that type which consist of a figure of an animal or the like having parts which may be moved in a life-like manner.

The objects of the invention are as follows:

First, to construct a toy of the character specified in such a way that it may be manipulated by a small child;

Second, to so construct the toy that the child's manipulation will cause certain members to move in a manner calculated to please and entertain the juvenile mind;

Third, to so construct the toy that the movable parts will be automatically restored to normal position when the operating influence is removed; and

Fourth, to so construct the toy that it has no exposed movable parts such as might pinch a child's fingers.

Other objects such as will be manifest in the following detailed description of the invention and particularly pointed out in the appended claims.

These objects are attained in the manner hereinafter set forth, reference being had to the accompanying two sheets of drawings wherein—

Figure 1 is a side elevation of a toy giraffe constructed in accordance with this invention;

Figure 2 is a rear elevation of the same;

Figure 3 is a top plan view thereof;

Figure 4 is a central vertical sectional view of the same with the parts in normal position; and

Figure 5 is a similar view with the parts in the opposite extreme to which they may be moved.

The toy comprises, primarily, a body portion 1 fixedly mounted upon legs 2 and provided with a movable tail 3, and a movable head 4 joined to the body 1 by a flexible neck 5.

At the lower portion of the body is a chamber 6 enclosed by means of covering 7 of cloth, leather or the like, externally marked to agree with the design upon the outside of the body member. Within this chamber 6 is a bar 8 pivotally mounted at its rear end

upon either the body 1 or between the hind legs 2.

Pivottally attached to the forward end of the bar 8 is a rod 9 extending upwardly through a bore 10 in the body 1, through the interior of the flexible neck 5, and having fixedly mounted upon its upper end the head 4.

The tail member 3 is pivotally mounted, at a point closely adjacent its inner end, to the rear of the body 1 and within a recess 11 formed therein. Secured to that portion of the tail 3 inwardly beyond its pivotal mounting is the rear end of a cord, wire, cable, or other flexible connection 12 which passes forwardly through a bore 13 in the body 1 and has its forward end secured to the bar 8 at a point adjacent the forward end of said bar.

Vertically slidable through a bore 14 in the body 1 is an operating rod 15 provided, at its lower end with a button 16 adapted to bear against the upper face of the bar 8 at a point substantially midway of its length. The upper end of the rod 15 projects into a chamber 17 formed in the back of the body 1 and enclosed by means of a covering 18 of cloth, leather, or the like, also marked externally to accord with the outer markings of the body 1. The upper end of the rod 15 is likewise provided with a button 19 adapted to be engaged and pressed through the covering 18 by the finger of the child or person who is manipulating the toy.

When the parts are in normal position, as shown in Figure 4, the bar 8 is maintained in raised position by means of a spring 20, the lower end of which is fastened to the bar 8 and the upper end of which is attached to the body 1. The movement of parts in this direction is limited by the complete expansion of the flexible neck 5. When the parts are in this position, the tail 3, owing to the preponderance of weight in its outer end, depends in a natural and realistic manner.

When it is desired to operate the toy, the button 19 is pressed inwardly, and the parts caused to assume the position shown in Figure 5. In this position the head 4 is pulled downwardly toward the body 1 with contraction of the neck 5, and the outer end of the

tail 3 is raised. The alternate pressing and release of the button 19 will cause a consequent nodding or bobbing of the head of the toy with synchronized wagging of its tail.

5 It is, of course, to be understood that the giraffe illustrated and described is merely one embodiment of this invention as it may, with equal facility, be applied to other figures. The toy need not, necessarily, be in 10 the form of an animal at all, as the principles are capable of a wide variety of adaptations. All such adaptations, as well as modifications in the size, form and location of parts, are contemplated as forming a part of this invention and must be so understood insofar as 15 they fall within the scope of the following claims.

What I claim is:

20 1. A toy giraffe comprising a body portion, a flexible neck extending from said body portion, a head secured to said neck, a tail pivotally secured to said body portion, an arm connected to the head portion and extending through a guide opening in the body portion, 25 a second arm pivotally connected at one end to the body portion and to the first arm at the opposite end, means connected to said second arm and to said tail, a push member contacting with said second arm and extending through the body portion, resilient means 30 for maintaining said neck in extended position and tail in lower position, said push member adapted to be pressed causing said neck to be contracted and said tail raised.

35 2. A toy giraffe comprising a body portion, a flexible neck extending from said body portion, a head secured to said neck, a tail pivotally secured to said body portion, said tail pivotally secured intermediate its length, an 40 arm connected to the head portion and extending through a guide opening in the body portion, a second arm pivotally connected at one end to the body portion and at its other end to the first arm, a member secured to 45 said second arm and to the portion of the tail projecting beyond the pivotal point, a push member slidably mounted in said body portion and contacting with said second arm in angular relation thereto, means for returning 50 said neck and tail to their original positions after said push member has been depressed.

55 3. A toy giraffe comprising a body portion, a flexible neck extending from said body portion, a head secured to said neck, a tail pivotally secured to said body portion, said tail pivotally secured intermediate its length, an arm connected to the head portion and extending through a guide opening in the body 60 portion, a second arm pivotally connected at one end to the body portion and at its other end to the first arm, a member secured to said second arm and to the portion of the tail projecting beyond the pivotal point, a push member slidably mounted in said body por-

tion and contacting with said second arm in angular relation thereto, means for returning said neck and tail to their original positions after said push member has been depressed, and a flexible covering extending 70 over said push member.

In testimony whereof I affix my signature.
JOHN J. SPARLOW.
